[57] CLAIM

The ornamental design for a container with cap, as shown and described.

DESCRIPTION

FIG. 1 is a front perspective view from above and one side of a container and cap incorporating our new design;

FIG. 2 is a top plan view thereof;

FIG. 3 is a front view thereof;

FIG. 4 is the underneath plan view thereof; and,

FIG. 5 is a perspective view with the cap being shown and separated from the container for completeness of illustration.

The broken line showing of the upper portion of the container is for illustrative purposes only and forms no part of the claimed design.
